DESIGN FOR A CARPET.

SPECIFICATION forming part of Design No. 14,530, dated January 1, 1884.

Application filed November 7, 1883. Term of patent 3½ years.

To all whom it may concern:

Be it known that I, ANDREW COCHRAN, a citizen of the United States, and a resident of Philadelphia, Pennsylvania, have invented a new and original Design for a Carpet-Pattern, of which the following is a specification.

My design is shown in the accompanying print; and it consists of leaf-patterns A and B, arranged upon a groundwork comprising 10 geometrical figures on a dotted field.

It should be understood that the four portions of the pattern B shown in the print are united in the complete pattern.

I claim—

The design for a carpet-pattern, said design 15 comprising the leaf-patterns A and B on a dotted and figured background, all substantially as shown and described.

In testimony whereof I have signed my name to this specification in the presence of two sub- 20 scribing witnesses.

ANDREW COCHRAN.
